UNITED STATES PATENT OFFICE.

THOMAS R. GAINES, OF NORWOOD, OHIO.

FASTENING DEVICE.

1,350,718.

Specification of Letters Patent. Patented Aug. 24, 1920.

Application filed September 15, 1917, Serial No. 191,639. Renewed July 8, 1920. Serial No. 394,806.

To all whom it may concern:

Be it known that I, THOMAS R. GAINES, a citizen of the United States, and a resident of the city of Norwood, in the county of 5 Hamilton and State of Ohio, have invented certain new and useful Improvements in Fastening Devices, of which the following is a specification.

This invention relates particularly to 10 means adapted to hold a loop or bend of a string, cord, or band at some intermediate point on the run thereof, either before or after application of the same to an object to be fastened.

15 One of the objects of the invention is to provide an improved means of the type set forth, capable of securely holding the loop or bend of the string, cord, or band, in its position, without tying it at either end, or 20 otherwise intertwining the ends to produce fastening coils, bows, twists, and the like.

Another object is the provision of an 25 arresting element for the said loop or bend, which shall be applicable thereto by simple apposition, or a mere sliding movement, and meanwhile be carried inside the string, cord or band, for protection and concealment.

A further object is to combine the said 30 arresting element with a check and a lock, of similar operation, whereby it can be stayed with progressively increasing firmness in a predetermined position.

Still another object is so to mount the 35 holding means upon the string, cord or band, that the loop or bend thereof may be stayed on one side or the other as desired, that is, kept from either enlarging or contracting at option, and also be fixed so as to render it immovable in both directions, if preferred.

40 Other objects and advantages of the invention will become apparent as the specification proceeds.

With the aforesaid objects in view, the invention consists of the novel construction, arrangement, and combination of parts hereinafter described, defined in the subjoined claims, and illustrated in their preferred embodiments by the annexed drawings, wherein like elements are designated by the 50 same reference characters throughout.

In the said drawings:—

Figure 1 is a perspective view representing the improved fastening device applied to a tape, such as may be employed for holding together a file of documents;

Fig. 2 is an enlarged longitudinal section

of the same form of the device, excepting the arresting element therein has been given a slightly different shape;

Fig. 3 is a view similar to that preceding, 60 but in addition shows how the device can be made to stay the loop or bend of the tape, string, cord or band, so that it cannot move in either direction, and likewise to hold different objects together so they may not come 65 apart;

Fig. 4 also is an enlarged longitudinal section illustrating a duplicate application of the aforesaid arresting element and check; and

Fig. 5 is a perspective view of a modified 70 form of construction.

In these views, the numeral "11" denotes a flexible or at least partly bendable member, which may be a string, cord, band, tape, or 75 the like, depending on the purpose for which the same is to be employed. Thus, a string may be used for doing up a parcel or package; a cord for holding back a curtain or drapery; a band to serve as a garter, armlet, 80 or bracelet; a tape to keep papers neatly bundled, etc., etc. As above stated, with reference to Fig. 1, the drawing shows a tape, which will suffice to demonstrate how the invention is carried out in practice.

85 The aforementioned tape, constituting the member 11, herein, may be made as usual of any suitable textile or other fabric, and is preferably formed tubular, as at 12, after the manner of a shoe lace or string. Like the 90 latter, it may also have a metal tip, at one end. The opposite end is perforated and eyeleted as at 14, for convenience in passing the tipped extremity therethrough and forming a loop 15. It is not necessary, however, to 95 have an eyelet, a noose, or a perforation to make the loop with, or that such loop be perfectly formed, as the invention is concerned only with staying at the proper point that end or portion of the hollow member which 100 is flexed or bent or otherwise passed around the object to be fastened.

An arresting element 21 is provided as the first means for staying the said loop or bend of the hollow member 11 in a predetermined position. This element, in the present exemplification of the fastening device, consists of a small globular or quasi-globular body, such as a grain of shot, for instance, and is lodged within the tubular 110 tape, or hollow part of the said member. Sufficient space is allowed for the element

21 to be moved or slid forward or back inside the tape or hollow member, in order to permit the formation of the loop 15 of greater or lesser extent therein, as may be required for practical usage, but as shown it is preferred that the element have only a driving fit, internally of the tape, so that it cannot be advanced or retracted through the latter without exerting thereon some slight external pressure. Obviously the only part of the member 11 which needs to be made hollow or tubular is that in which the bending action of the slideable element occurs.

15 When the loop 15 is to be stayed on the outside simply, that is, only to prevent enlargement thereof, the element 21 in such case will be located outwardly with relation to the eyelet 14, or corresponding portion of the tape 11, as illustrated in Fig. 1 of the drawing, and similarly in Figs. 2, 4 and 5. By sliding the element close to the eyelet, or the equivalent thereof, it will operate to maintain the loop substantially fixed upon the object encircled thereby, offering enough resistance to prevent slackening or enlargement in normal conditions. If, on the other hand, it be desired to preclude the narrowing in of the loop, then the element 21 should be positioned as indicated on the right hand side of Fig. 3, in which case the movement of the eyelet will be arrested as soon as it has reached the desired point upon being impelled in an inward direction. The size of the loop or bent portion of the hollow member can thus be gaged so as to suit any requirement, and the same will not vary after adjustment, unless the member, or its looped part, be made elastic for some specific purpose, and in that event the arresting member would still retain its relative location.

45 In Fig. 3, above referred to, it will be observed that there are two arresting elements 21, one situated on each side of an apertured object 22, of which but a fragment is shown. It can readily be perceived, however, that the object is caught and held between the pair of arresting elements, which co-act in maintaining the same at the point required.

50 A second means for staying the looped or bent end of the member 11 in the desired position is provided in the form of a check 25, which is an auxiliary to the before described arresting element 21. The check 25 is placed exteriorly of the said member and may conveniently consist of a slip-knot of the same fabric as the tape, or else of an 55 axially bored bead slideable on the latter, toward and away from the said element. By preference, a snug fit is effected between the said check or bead 25 and the outer face of the hollow member, to induce a slight 60 frictional interengagement. It will be noted

that the arresting element and its auxiliary check combine in resisting either enlargement or contraction of the loop 15, or in other words the shifting of the stayed end of the member 11 in one direction or the other or both ways, according to the position which they occupy relatively thereto, as represented in the several figures of the drawing.

65 To insure greater firmness and positively set the looped or bent end of the member 11 in a chosen position a third factor is resorted to in the nature of a lock 31, for the conjoined arresting element and auxiliary check hereinbefore disclosed. As shown in Fig. 80 1, this lock may have the form of a double slip-knot, of same material as the tape 11 and adapted slightly to compress the same, oppositely to the shot 21, the action whereof it is to expand the tubular tape, as will be 85 observed. But, beads 31^a may be used instead, as suggested in the other views, wherein the locks appear of same shape and structure as the check beads 25, previously described.

90 Fig. 5 illustrates a modification of the invention particularly adapted for use where it is not convenient to have a loop on the member 11 previously to its being applied, but nevertheless is desirable to provide a 95 means of promptly forming such loop as may be needed for the purpose to be accomplished. In this modified construction, the eyelet is supplemented, and may be replaced altogether, by a wire loop or doubled hook 100 35, of sufficient internal dimensions to admit the free passage, at or near the base thereof, of the outdrawn end of the member 11, with the arresting element 21, and check 25, carried thereby. The apex of the triangle 105 presented within the loop or hook 35 is narrowed to sufficient extent to stop the said parts 21 and 25, and prevent their slipping back through the loop, when the latter has been drawn tightly around or upon the object 110 on which the fastening device is employed.

Various modifications may be embodied in the device in accordance with the user's choice and discretion. Thus, for example, 115 the lock 31 may have a pendant 36, with an eye 37, as illustrated in Fig. 1, to permit insertion of the tipped end 13 of the member 11 and subsequent formation of a supplemental loop, in a manner that is well understood. The arresting element may be more or less pointed in both ends, like that denoted by 21^a in Fig. 2. A second arresting element 21^b may be introduced between the check 25 and the lock 31^a, as in Fig. 4. The 120 opposite ends of the member 11 may be doubled upon themselves and eyeleted, as at 14^a, 14^b, Fig. 5; and so on *ad libitum*.

125 Obviously, this improved fastening device can be put to many uses besides those to 130

which allusion has already been made. It may be employed advantageously as a substitute for rubber-bands, which as generally known soon lose their inherent elasticity and

5 snap off in two or more parts when stretched, particularly after some exposure. It may well replace also the common form of shoe-lace, and unlike the latter, does not require to be tied at the ends by a bow-knot or otherwise.

10 Analogously, it is available for holding together the opposite edges of corsets, leggings and other articles of wearing apparel, or parts thereof, such as waist-bands, belts and girdles.

15 It can further be used in connection with various forms of closures, for instance when tying a string, tape or ribbon around the mouth of a bag to keep it closed. In surgery, it will answer as a safe and quickly

20 responsive fastener for a tourniquet, and so on through a wide range of applications in different arts, trades and manufacture.

Having described my invention, what I desire to secure by Letters Patent, and claim

25 is:—

1. A fastening device including a tubular member capable of forming a loop or bend, and an arresting element operable to stay the latter by being moved thereagainst with-
30 in the said tubular member.

2. A fastening device including an expansible hollow member having one end adapted to be bent upon some intermediate point along the run thereof, and an arresting element of greater width than the internal diameter of said member movable therethrough toward or away from its said end.

3. A fastening device including a hollow member capable of being looped or bent upon itself at one end, an arresting element within said member movable toward or away from the loop or bend thereof, and a check adapted to be positioned against said ele-
45 ment.

4. A fastening device including a hollow member capable of forming a loop or bend, an element designed to stay the latter by moving thereagainst within said member, and a check movable toward or away from said element upon the member's exterior surface.

5. A fastening device including a hollow expansible member, an arresting element of greater diameter adapted to be driven through said member so as to stay a loop or

bend on the run thereof, and a movable check for said element normally held to the exterior of the member by frictional engagement.

60

6. A fastening device including a hollow member capable of forming a loop or bend, an arresting element for the latter movable internally of said member, a check for said element adapted for movement toward or 65 away from the same, and a lock designed to coact with said check in maintaining the arresting element in a predetermined position.

7. A fastening device including a hollow pliable member, an arresting element movable inside the latter so as to stay a bend or loop on the run thereof, a check for said element, and a lock adapted to compress said member while being placed in juxtaposition to said check.

70

8. A fastening device including a hollow expansible member, an arresting element of larger caliber adapted to be impelled through said member against a loop or bend on the run thereof, a check adapted to be positioned adjacent to said element, and a compressing lock slidable upon the exterior of the member contiguous to said check.

80

9. A fastening device including a hollow member capable of forming a bend or loop 85 at one of its ends, an arresting element adapted to stay said bend or loop by moving through said member, a check for said element, a lock designed to coöperate with said check in keeping the arresting element in a 90 given position, and means on said lock available to hold the other end of the hollow member in folded condition.

10. A fastening device including a hollow member provided with a differentially ap- 95 pertured loop through which one end of said member can be inserted to form a bend in the run thereof, a slidable element inside the member capable of being passed through the wider portion of said loop but designed to be 100 stopped by its narrower portion upon completion of said bend, and means serving to maintain said element in a firm position against the narrowed part of the loop.

Signed at the borough of Manhattan, in 105 the county of New York and State of New York, this 14th day of September, A.D. 1917.

THOMAS R. GAINES.
